CLEARING MECHANISMS FOR THE WORK-SUPPORTS
OF FASTENING-INSERTING MACHINES
Filed March 29, 1944

UNITED STATES PATENT OFFICE

2,387,305

CLEARING MECHANISM FOR THE WORK SUPPORTS OF FASTENING-INSERTING MACHINES

John F. Standish, Winthrop, Mass., assignor to United Shoe Machinery Corporation, Flemington, N. J., a corporation of New Jersey

Application March 29, 1944, Serial No. 528,510

13 Claims. (Cl. 1—32)

This invention relates to clearing mechanism, and especially to means for preventing the deposit of chips or other waste in the driver-passages of fastening-inserting machines.

In heel-attaching machines, such as that disclosed in Letters Patent of the United States No. 2,178,615, Standish et al., November 7, 1939, the work-supporting jack has passages containing reciprocating drivers by which nails are inserted through the heel-seat of a jacked shoe into an applied heel to attach said heel to the shoe. Upon the top of the jack, waste material, such as chips left in a hole in the heel-seat and heel from which a temporary attaching screw has been removed, may be deposited. When the fastening-transferring member or loader-block comes forward to make its delivery to the jack-passages, this material may be pushed forward over the front driver-passages, and upon return of the loader-block some of the waste material may be dragged back over the rear passage. The pieces may be of sufficient size to bridge the passages and prevent the entrance of the nails, while some of the material may enter, and, gathering upon the upper ends of the drivers, so deflect the points of the nails that they will be inserted incorrectly. An object of my invention is to render impossible the retention of waste upon the top of the work-support.

I attain the above object by directing a waste-removing air-current across the top of a work-support or jack in which are driver-passages, and, to make certain that the top is cleared of the waste immediately before the arrival of the transferring member, the air-current is created in the advance movement of said member above the work-support. Preferably, this is effected by a member movable with the actuating mechanism for the transferring member, and, to ensure the correctness of the time of action of the air-current with respect to the travel of the transferring member, this may be varied. More specifically, I associate with the jack of a heel-attaching machine, through the top of which jack are driver-passages supplied with nails by a reciprocating loader-block, a cylinder, a piston movable in the cylinder, a tube leading from the cylinder and directed toward the jack-top, a spring by which the piston is urged toward the opening of the tube into the cylinder, and means for retracting the piston and releasing it to receive the action of the spring. Upon this release, the spring-actuated movement of the piston delivers from the tube across the jack-top an abrupt and strong current of air, which is highly effec-

tive in disposing of the waste. The retraction and release of the piston may be effected directly from the mechanism by which the loader-block is reciprocated, and thus the delivery of the air-current readily synchronized with the travel of the loader-block. In the organization herein disclosed, a lever is connected to the piston and spring, and an arm is movable with an oscillatory shaft from which the loader-block is reciprocated, the arm in its movement first engaging the lever to retract the piston and tension the spring, and then releasing the lever and piston to permit the spring to act and create the air-current from the tube.

A particular embodiment of the invention is illustrated in the accompanying drawing, in which:

Fig. 1 shows the mechanism of this invention in side elevation, in place upon a heel-attaching machine;

Fig. 2 is an enlarged broken side elevation of the clearing mechanism; and

Fig. 3 is an enlarged sectional detail on the line III—III of Fig. 1.

At 10 appears a portion of the frame-column of a heel-attaching machine, which is that of the previously mentioned Standish et al. patent. In a jack 12 rising from the front of the machine are vertical passages 14, in which reciprocate nail-inserting drivers 16. Upon the top 18 of the jack, the shoe to be heeled is placed with its insole resting upon said top. If a shoe with an applied heel has previously been drilled through the heel-seat into the heel and a temporary screw inserted, the hole which is left after the screw has been removed and the last pulled is liable to contain chips resulting from these operations. Upon inverting the shoe over the jack, this hole comes near the center of the group of driver-passages, and the chips falling from the hole will gather upon the jack-top. To deliver the attaching nails to the jack-passages, a loader-slide 20 is mounted to reciprocate upon the frame to present its block 22 beneath the foot-plate 23 in nail-receiving position, as illustrated in Fig. 1, or in nail-delivering position above the jack. The loader-slide is movable under the power of the machine, controlled by the operator through the depression of a hand-lever 25. The reciprocation is effected from a shaft 24 by mechanism which includes a friction or overload device 26, belt-gearing 28, a shaft 30, worm-gearing 32, a shaft 34, a crank-disk 36, and co-operating levers 38 and 40. The lever 38 is fast upon a shaft 42, while the lever 40 is loose

upon the shaft and is actuated by the lever 38. When the loader-block 22 makes its delivery of nails to the jack, its underside travels close to the jack-top 18, and its forward edge will tend to sweep over the driver-passages 14 any chips which may have fallen from the shoe, previously operated upon. Reverse movement of the loader-block may drag the chips beneath it across the rear passage. The passage-openings may become so obstructed the loader-block cannot deliver its nails, or accumulating upon the driver-ends, the chips may so act upon the nail-heads that, instead of toeing in, the points of the nails will incline outwardly and perhaps break through the wall of the heel. These conditions the present invention guards against.

A cylinder 50 has formed with it lugs 52, through openings in which it is attached to the interior of the frame-column 10 by screws 53. Made into an opening in the closed upper end of the cylinder is a tube 54, leading to a point within and at one side of the column just above the path of the loader-slide 20. Here, it is made into a threaded opening in the wall by a union-elbow 56. Into this opening outside the column-wall a union-elbow 58 is threaded, this carrying a piece 60 of tubing with an angular end terminating in a nozzle 62; having a contracted outlet-opening 64. By turning the tube 60 in the union 58 and the union itself in the column, slightly making or unmaking the thread, the nozzle-opening may be adjusted in intersecting planes, in which the tubing 60 is swung and in which its angular end is movable, to direct the discharge from the opening upon any desired area of the jack-top 18. A piston 66 is movable within the cylinder 50, and is joined by a link 68 to a lever 70 fulcrumed at 72 upon an extension 14 from the cylinder. A tension-spring or springs 76, connected to the lever and to a lug at the upper end of the cylinder, holds the piston normally up to the cylinder-head. To the shaft 42, to which is secured the actuating lever 38 for the loader-slide, is attached an arm 78 having pivoted upon its end toward the cylinder a contact-piece 80. This contact-piece is held yieldably by an expansion-spring 82 at an angle determined by a stop-screw 84. The angular end of the contact-piece lies normally just above and close to the outer edge of a surface 86 upon a contact-block 88 fixed to the lever 70.

Assuming that the operator has just removed from the jack 12 a shoe with its attached heel, there may have been deposited upon the jack-top 18 chips, as indicated at c in Fig. 1. In preparation for the heeling of the succeeding shoe, the operator depresses the lever 25, which causes the loader-block 22 with its load of nails to travel forward from the foot-plate 23. As the shaft 42 rocks counterclockwise in effecting this movement of the loader-block through the levers 38 and 40, the arm 78 turns with it in the same direction. By the engagement of the contact-piece 80 with the block-surface 86 upon the lever 70, said lever is turned clockwise, lowering the piston 66 in the cylinder 50 and tensioning the spring 76. During this movement, air is being drawn in idly through the nozzle-opening 64 and tubes 60 and 54. As the loader-block is approaching the jack, the end of the contact-piece will have gradually shifted outwardly across the surface 86, because of the downward divergence of the arcs described by the points of engagement of the lever 70 and the arm 78 about the axis of the fulcrum 72 and that of the shaft 42, respectively. When the

loader-block is still somewhat removed from the jack-top, the contact-portions of the lever and arm will separate, this being shown in dash-lines in Fig. 2 as about to occur. The lever will therefore be released from the arm, and the spring will abruptly retract the piston, carrying it to the head of the cylinder. There will be discharged through the nozzle-opening 64 a sudden and strong blast of air, which, because of the position of the nozzle, will be directed upon the jack-top, completely clearing this. Therefore, when the loader-block reaches the jack to deliver its nails to the passages 14, there will be no waste material to be forced into said passages, and these will not become clogged. As the loader-block is returned by its actuating-mechanism to its normal position beneath the foot-plate, the arm 78 rises and the contact-piece 80, engaging the end of the now raised lever 70, yields against its spring 82 and, when it reaches the end of its stroke, is carried by said spring to its initial position above the surface 86. The operator proceeds with the attachment of the next heel and the clearing mechanism is ready for operation upon the succeeding actuation of the lever 25, following the removal from the jack of the heeled shoe. Since the work done by the clearing mechanism merely consists in drawing air into the nozzle and tensioning the spring 76, the additional load which it places upon the driving mechanism is negligible, and the resistance of the overload device 26 to releasing need not be increased. Thus, the protection which this overload device affords the nail-supplying mechanism is not affected. It is to be observed that the clearing mechanism is in the form of an independent unit, which may be applied to the fastening-inserting machine without alteration in the structure of the machine itself. The time at which the arm 78 releases the piston-lever 70 may be varied by adjustment of the screw 84, and therefore the relation of the contact-piece 80 to the edge of the block 88. Thus, the exact period in the travel of the loader-block at which the jack-clearing action occurs may be determined.

Having described my invention, what I claim as new and desire to secure by Letters Patent of the United States is:

1. In a fastening-inserting machine, a work-support provided with a passage opening through the top of the support, a driver movable in the passage to insert a fastening in the work, and means for directing an air-current across the top of the support prior to the inserting movement of the driver.

2. In a fastening-inserting machine, a work-support provided with a passage opening through the top of the support, a fastening-driver movable in the passage, a fastening-transferring member movable over the top of the support, and means for directing an air-current across the top of the support in advance of the movement above said support of the transferring member.

3. In a fastening-inserting machine, a work-support provided with a passage opening through the top of the support, a fastening-driver movable in the passage, a fastening-transferring member movable over the top of the support, actuating mechanism for the transferring member, and means including a member movable with the actuating mechanism for directing an air-current across the top of the support.

4. In a fastening-inserting machine, a work-support provided with a passage opening through the top of the support, a fastening-driver mov-

able in the passage, a fastening-transferring member movable over the top of the support, means for directing an air-current across the top of the support in advance of the movement above said support of the transferring member, and means arranged to vary the time of delivery of the air-current.

5. In a fastening-inserting machine, a work-support provided with a passage opening through the top of the support, a fastening-driver movable in the passage, a fastening-transferring member movable over the top of the support, actuating mechanism for the transferring member, means including a member movable with the actuating mechanism for directing an air-current across the top of the support, and means arranged to vary the time at which the movable member affects the air-directing means.

6. In a heel-attaching machine, a jack provided at its top with passages, fastening-drivers reciprocable in the passages, a reciprocatory loader-block delivering to the passages, a cylinder, a piston movable in the cylinder, a tube leading from the cylinder and directed toward the jack-top, a spring by which the piston is urged toward the opening of the tube into the cylinder, and means for retracting the piston and releasing it to receive the action of the spring.

7. In a heel-attaching machine, a jack provided at its top with passages, fastening-drivers reciprocable in the passages, a reciprocatory loader-block delivering to the passages, a cylinder, a piston movable in the cylinder, a tube leading from the cylinder and directed toward the jack-top, an oscillatory lever connected to the piston, a spring acting upon the lever to urge the piston toward the opening of the tube into the cylinder, and an oscillatory arm movable to actuate the lever and to release it to permit the spring to act.

8. In a heel-attaching machine, a jack provided at its top with passages, fastening-drivers reciprocable in the passages, a reciprocatory loader-block delivering to the passages, a cylinder, a piston movable in the cylinder, a tube leading from the cylinder and directed toward the jack-top, an oscillatory lever connected to the piston, a spring acting upon the lever to urge the piston toward the opening of the tube into the cylinder, an oscillatory arm, and a contact member yieldable upon the arm and movable in engagement with the lever to actuate it and to release it to permit the spring to act.

9. In a heel-attaching machine, a jack provided at its top with passages, fastening-drivers reciprocable in the passages, a reciprocatory loader-block delivering to the passages, a cylinder, a piston movable in the cylinder, a tube leading from the cylinder and directed toward the jack-top, an oscillatory lever connected to the piston, a spring acting upon the lever to urge the piston

toward the opening of the tube into the cylinder, an oscillatory arm, a contact member yieldable upon the arm and movable in engagement with the lever to actuate it and to release it to permit the spring to act, and means arranged to vary the normal position of the contact member upon the arm.

10. In a heel-attaching machine, a jack provided at its top with passages, fastening-drivers reciprocable in the passages, a reciprocatory loader-block delivering to the passages, an oscillatory shaft by which the loader-block is reciprocated, a cylinder, a piston movable in the cylinder, a tube leading from the cylinder and having a nozzle delivering to the jack-top, a spring by which the piston is urged toward the opening of the tube into the cylinder, and means movable by the shaft for retracting the piston and releasing it to receive the action of the spring.

11. In a heel-attaching machine, a jack provided at its top with passages, fastening-drivers reciprocable in the passages, a reciprocatory loader-block delivering to the passages, an oscillatory shaft by which the drivers are reciprocated, a cylinder, a piston movable in the cylinder, a tube leading from the cylinder and having a nozzle delivering to the jack-top, a lever fulcrumed upon the cylinder and connected to the piston, a spring joining the lever to the cylinder, and an arm movable by the shaft in engagement with the lever.

12. In a heel-attaching machine, a jack provided at its top with passages, fastening-drivers reciprocable in the passages, a reciprocatory loader-block delivering to the passages, an oscillatory shaft by which the drivers are reciprocated, a cylinder, a piston movable in the cylinder, a tube leading from the cylinder and having a nozzle delivering to the jack-top, a lever fulcrumed upon the cylinder and connected to the piston, a spring joining the piston to the cylinder, an arm movable by the shaft in engagement with the lever, a contact member pivoted upon the arm for engagement with the lever, a stop-screw by which the position of the contact member may be adjusted, and a spring interposed between the arm and the contact member to force said contact member against the stop-screw.

13. In a heel-attaching machine, a frame-column in which is an opening, a jack supported upon the column and provided in its top with driver-passages, means situated within the column for producing an air-current, a tube-section leading from the air-current-producing means to the column-opening, an outer tube-section leading from the column-opening and having a nozzle directed toward the jack-top, and means for supporting the outer tube-section for movement to vary the position of the nozzle in intersecting planes.

JOHN F. STANDISH.
